Primary Examiner — Vy N Koenig(74) *Attorney, Agent, or Firm* — Grant IP. Inc.(57) **CLAIM**

The ornamental design for a pipette tip retention sheet, as shown and described.

DESCRIPTION

FIG. 1 is a top view of a pipette tip retention sheet embodiment having hole-to-edge offsets of varying widths;

FIG. 2 is a long side view of the sheet shown in FIG. 1; FIG. 3 is a short side view of the sheet shown in FIG. 1; and, FIG. 4 is a top perspective view of the sheet shown in FIG. 1.
